(57) **CLAIM**

The ornamental design for a soldering tool grip, as shown and described.

DESCRIPTION

FIG. 1 is a perspective view of a soldering tool grip according to a first embodiment;

FIG. 2 is a top view of the soldering tool grip of FIG. 1; FIG. 3 is a bottom view of the soldering tool grip of FIG. 1; FIG. 4 is a left side view of the soldering tool grip of FIG. 1;

FIG. 5 is a right side view of the soldering tool grip of FIG. 1;

FIG. 6 is a front view of the soldering tool grip of FIG. 1; FIG. 7 is a rear view of the soldering tool grip of FIG. 1; FIG. 8 is a perspective view of a soldering tool grip of FIG. 1 shown in use on a soldering tool;

FIG. 9 is a perspective view of a soldering tool grip according to a second embodiment;

FIG. 10 is a top view of the soldering tool grip of FIG. 9; FIG. 11 is a bottom view of the soldering tool grip of FIG. 9;

FIG. 12 is a left side view of the soldering tool grip of FIG. 9;

FIG. 13 is a right side view of the soldering tool grip of FIG. 9;

FIG. 14 is a front view of the soldering tool grip of FIG. 9; FIG. 15 is a rear view of the soldering tool grip of FIG. 9; FIG. 16 is a perspective view of a soldering tool grip of FIG. 9 shown in use on a soldering tool;

FIG. 17 is a perspective view of a soldering tool grip according to a third embodiment;

FIG. 18 is a top view of soldering tool grip of FIG. 17; FIG. 19 is a bottom view of soldering tool grip of FIG. 17; FIG. 20 is a left side view of soldering tool grip of FIG. 17; FIG. 21 is a right side view of soldering tool grip of FIG. 17; FIG. 22 is a front view of soldering tool grip of FIG. 17; FIG. 23 is a rear view of soldering tool grip of FIG. 17; and, FIG. 24 is a perspective view of a soldering tool grip of FIG. 17 shown in use on a soldering tool.

The broken lines shown represent environmental subject matter and portions of the soldering tool grip that form no part of the claimed design.
